UNITED STATES PATENT OFFICE.

FERDINAND RIES, OF NEW YORK, N. Y.

DIAMOND GRINDER.

1,415,118.

Specification of Letters Patent. Patented May 9, 1922.

Application filed April 18, 1918, Serial No. 229,218. Renewed October 15, 1921. Serial No. 503,051.

To all whom it may concern:

Be it known that I, FERDINAND RIES, residing at New York, in the county of New York and State of New York, have invented 5 a new and Improved Diamond Grinder, of which the following specification is a full disclosure.

This invention deals with mechanism for cutting and polishing precious stones, such 10 as diamonds, and it proposes a simple, compact, inexpensive and convenient apparatus for this purpose.

Heretofore devices for successfully polishing stones have been commercially available, 15 but said devices have been of restricted capacity because of various mechanical inconveniences the necessity of releasing the gem in order to reposition it for different facets and have been inconvenient to use.

20 In order that the present invention may be more clearly understood and carried into effect, the same is hereinafter disclosed by way of an improved embodiment thereof shown in the accompanying drawings, in 25 which:

Fig. 1 is a left-handed side elevation of the dop-holder. Fig. 2 is a rear elevation thereof. Fig. 3 is a section on the line III—III of Fig. 2. Fig. 4 is a righthanded side 30 elevation of the dop-holder. Fig. 5 is a section on the line V—V of Fig. 1; and Fig. 6 is a perspective of the intermediate angling block.

The present construction comprises elements for angularly positioning the gem, the dop-holder illustrated providing micrometer angular adjustments in all of the primary directions, i. e., in all of the geometrical planes necessary for the accurate grinding 40 of the facets of a diamond. This dop-holder comprises a stem 159 in the nature of a base adapted to be affixed to a suitable adjustable part for changing the elevation of the gem. Preferably, this attachment is 45 readily separable and to that end an extension 117 having a bifurcation 118 which receives the shank 158 of the dop-holder. The knurled nut 166 is screw-threaded to an extension 167 so that the dop holder may be 50 clamped in extension 117 as shown by Fig. 1. The stem 159 is provided with a series of graduations 160 corresponding with a scratch mark on the extension 117; thereby enabling the dop holder as a whole to be 55 swung through any desired horizontal angle with relation to extension 117. The lower

part of the stem 159 is bifurcated to provide the side-wings 161, and locked therebetween is the block 170 shown by Fig. 6; said block being pivoted to swing through any desired 60 vertical angle. This is accomplished by a pivot pin 162 which passes through a hole 171 and is rigidly secured to the block by means of a key-pin 185 entering the hole 176 in the pivot-pin. A nut 163 is secured at 65 one end of the pivot pin and the other end has a head to which is rigidly fastened a dial hand 164 cooperating with the graduations 165 on the side of the corresponding wing 161. By these means the angular relation of the block 170 to the stem 159 is indicated, and a micrometer screw 190 is provided for the purpose of accurate adjustments. This micrometer screw consists of a screw proper 186 cooperating with the 75 worm 174 cut in the block 170; said screw 186 being journaled between the side-pieces 188 and the stem 159 by means of the bearings 187. A pin 189 secures a collar 190 to the screw and a part 192 affords a grip on 80 said collar. The collar is provided with graduations 191 cooperating with a suitable scratch-mark on the side-piece 188. This constitutes a micrometer adjustment since each of the divisions 191 may represent a 85 degree or a fraction of a degree, as may be desired, and as a consequence, a very accurate angling of the piece 170 is available.

In order to obtain an adjustment through a vertical angle in a plane at right-angles 90 to that above mentioned, the block 170 has a hole 172 at right-angles to the hole 171 and a pin 184 passes through a drill hole 175 and keys the pivot-pin 178 to the block 170. A dop-support 201 provides side-wings which are pivoted to the pivot-pin 178, and a nut 180 is secured to one end of the pin 178 and a pointer 179 is secured to the other end. This pointer cooperates with graduations 181 on the support 201. Within the support is journaled a micrometer screw 194 meshing with the worm 173 cut in the block 170. The worm has end-bearings 195 which ride respectively in the socket 202 and the collar 196 affixed to the support 100 201. The graduated-collar 198 is pinned at 197 to the bearing 195 and has a part 199 to facilitate its turning. This collar 198 is provided with graduations 200 which co-operate with a suitable scratch-mark on the support 201. By these means, a micrometer 105 adjustment in a vertical plane at right-

angles to the first-mentioned angular adjustment 164 is provided. The dop-support 201 extends in offset relation with the above-mentioned parts and has a boss 204 5 providing a tapered socket to receive a tapered end 205 of a dop-holder 214. The latter has a screw-threaded stem 206, and a knurled-collar 207 serves to secure it positively in the part 201. The dop-holder 214 10 is provided with peripheral graduations 215 which may cooperate with a suitable scratch-mark on the part 201 to enable it to be set in any desired horizontal angle in the same. The gem is seated in a socket 212 15 in the extremity of a dop 210 and this dop is held in a tapered socket 220 by means of a screw 209 entering a screw-threaded aperture 211; said screw having a knurled upper end 208.

20 The gem is held in its seat by a number of prongs 217 which have their extremities 218 cut at angles corresponding to the facets of the stone so as to grip it and yet expose a very substantial portion of the 25 stone for cutting purposes. The shanks of the prongs 217 are received by sockets 216 in the dop holder and screws 219 serve to clamp them firmly in place. These prongs 217 are interchangeable and in the process 30 of exposing a new facet they are shifted step by step throughout the different sockets 216 in such a manner that the stone is always held rigidly grasped by a plurality of prongs.

35 The claims of this application are direct-

ed to the dop holder per se, and the novel features of construction of the bridge, carriage, and related elements will be made the subject matter of applications constituting divisions of this case.

Having thus revealed this invention, I claim as new and desire to secure the following combinations of steps and elements, or equivalents thereof, by Letters Patent of the United States:—

40

45

I claim:

1. A unitary dop holder combining an intermediate block having two worms in transverse planes; a base piece having a micrometer screw engaging one of said worms; and a dop holder having a micrometer screw engaging the other worm, whereby a micrometer adjustment in two transverse planes is provided.

2. A unitary dop holder combining a base piece adapted to be secured to a carriage; a gem holder; a block intermediate said parts and pivoted at right angles to each; a micrometer adjusting screw for determining the angular relation between said second-mentioned part and said intermediate block.
